UNITED STATES PATENT OFFICE

HENRY H. BALTZLEY, OF ASSUMPTION, ILLINOIS, ASSIGNOR OF ONE-HALF
TO ELIJAH WALKER, OF SAME PLACE.

HOT-AIR ATTACHMENT FOR HEATING-STOVES.

SPECIFICATION forming part of Letters Patent No. 650,745, dated May 29, 1900.

Application filed February 23, 1900. Serial No. 6,281. (No model.)

To all whom it may concern:

Be it known that I, HENRY H. BALTZLEY, a citizen of the United States, residing at Assumption, in the county of Christian and State 5 of Illinois, have invented certain new and useful Improvements in Hot-Air Attachments for Heating-Stoves; and I do hereby declare the following to be a full, clear, and exact description of the invention, such as will enable others skilled in the art to which it appertains to 10 make and use the same.

This invention aims at economy in the consumption of fuel for heating purposes and to utilize a maximum percentage of the evolved 15 heat from a given quantity of fuel for effective heating.

The device is intended for use in connection with any form of stove having an opening in its top in which it can be suspended, 20 the lower end of the device terminating a sufficient distance from the fire to avoid being burned and from the feed-door opening, so as not to obstruct the free access to the stove for replenishing the fire, stirring the fuel, or 25 like purpose.

For a full description of the invention and the merits thereof and also to acquire a knowledge of the details of construction of the 30 means for effecting the result reference is to be had to the following description and the drawings hereto attached.

While the essential and characteristic features of the invention are necessarily susceptible of modification, still the preferred embodiment of the invention is illustrated in the 35 accompanying drawings, in which—

Figure 1 is a sectional detail of a stove, showing the heating attachment in position. Fig. 2 is a perspective view of the device. Fig. 3 is 40 a perspective view of the lower section of the attachment. Fig. 4 is a view of the upper section inverted.

Corresponding and like parts are referred to in the following description and indicated 45 in all the views of the drawings by the same reference characters.

The invention may be characterized as a heating attachment; and it consists, essentially, of a hollow body adapted to be suspended 50 in the stove-top opening and having

its lower end closed and provided with air-ducts at its sides opening at their lower ends in the lower portion of the body and at their upper ends exterior to said body and at a point above the top of the stove and below 55 the upper end of the said body.

The body 1 may be of any cross-sectional outline and of any diameter and length and as shown is of circular form in horizontal section and is closed at its bottom and open at 60 the top. This body 1 is adapted to be suspended in the opening in the top of a heating-stove 2 in such a manner as to have a portion, as 3, projecting above the top of the stove, the lower closed end approaching to 65 within a short distance of the fire, so as not to obstruct the door-opening of the stove, through which fuel is supplied to the fire and access to the stove is had; yet being located a distance from the fire, so as not to be burned. 70 An outer flange 4 is provided intermediate of the length of the body 1 and fixed into the rabbet surrounding the opening in the top of the stove and makes a tight joint therewith to prevent escape of smoke and gases. 75 The portion 3, projecting above the top of the stove, may be suitably ornamented or embellished, so as to provide a pleasing and finished appearance.

The ducts 5 are located at the sides of the 80 body and interior thereof and their lower ends extend to within a short distance of the bottom of the body and their upper ends communicate with the external air at a point above the top of the stove and at a distance 85 from the top edge of the part 3. These ducts may be provided in any desired number and may have any capacity best adapted to the size of the attachment and the work required thereof. While the ducts may be formed in 90 any way found most advantageous, it is preferred to construct them of strips which are deflected intermediate of their longitudinal edges, the latter constituting flanges which are bolted or otherwise secured to the inner 95 wall of the body.

In the practical construction of the device it has been found most advantageous to construct the same of two sections detachably fitted by means of a slip-joint, the lower sec- 100

tion 6 having the outer flange 4 formed at its upper end and provided upon its inner side with the ducts 5. The part 3 constitutes the upper section and is indented at its lower end, as shown at 7, at points corresponding with the upper ends of the ducts 5, so as to receive said ends when the sections 3 and 6 are fitted together. The sections may be either cast or struck up from sheet metal, and in some instances it is preferred to have the part 6 composed of halves or sections which are secured together, the strips 8, constituting the ducts 5, serving as means to overlap the side joints and to secure the sections or parts together.

When the attachment is applied to a heating-stove, the lid or cover is removed and the attachment is suspended in the opening by means of the outer flange 4 resting in the rabbet surrounding the opening from which the lid or cover has been removed. When the fire is started, the air contained in the body is heated and rising creates a partial vacuum in the bottom portion of the body and cold air rushes into the ducts 5 and is in turn heated and escapes from the top of the body. The circulation of air thus established is maintained so long as there is any fire in the stove. For heating a room or apartment other than that in which the stove is located it is only necessary to attach a pipe to the upper portion of the body 1, when the hot air will pass to said room through the pipe as a conductor.

35. The heating attachment will be constructed in different sizes, so as to fit openings of different diameters, and will be cast or formed of sheet metal, and in some instances will be formed of a single piece, the manner of construction being immaterial within the purview of the invention.

Having thus described the invention, what is claimed as new is—

1. The herein-described heating attachment for stoves, comprising a lower section closed at its bottom and having an outer flange at its top edge, an upper section fitted snugly at its lower end in the upper end of said lower section, and vertical longitudinal air ducts or passages arranged in the lower section and formed independently of said upper section, and having their lower ends terminating adjacent to the bottom of the lower section and their upper ends terminating exterior to the top section, substantially as described.

2. A heating attachment comprising a lower section closed at its bottom and having ducts upon its inner side terminating at their lower ends a short distance from the bottom, and an upper section fitted by a slip-joint to the lower section and having indentations to receive the upper ends of the aforesaid ducts and constituting inlets therefor, substantially as set forth.

3. The herein-described heating attachment for stoves, comprising a lower section closed at its bottom and having an outer flange at its top edge, strips deflected intermediate of their longitudinal edges and secured to the inner side of the said section and forming ducts, and the upper section fitted by a slip-joint to the lower section and having indentations to receive the upper ends of the aforesaid ducts and constituting inlets therefor, substantially as set forth.

In testimony whereof I affix my signature in presence of two witnesses.

HENRY H. BALTZLEY. [L. S.]
